THERMOSTATIC CONTROL DEVICE

Frank T. Hawke, Paris, Ky., assignor to Electric Steam Radiator Corporation, Paris, Ky., a corporation of Michigan

Application January 20, 1954, Serial No. 405,215

7 Claims. (Cl. 200—138)

This invention relates to a thermostatic control for an electrical circuit and is especially concerned with a control employing a bimetal heat responsive element to actuate an electric switch.

An exemplary application of the invention lies in thermostatically closing and opening a circuit for an electrical appliance such as a space heating device. It is a primary object of this invention to provide a thermostat structure which is durable yet simpler and less expensive of manufacture than structures now known in the art.

The invention is carried out in part by utilizing the inherent resiliency of the bimetal heat responsive element in such a way as to eliminate the necessity for additional spring structure to maintain proper contact between the bimetal element and a switch and a regulator element. Another part of the invention is carried out by so adapting the base of the device that lead-in wires are clamped in position between the base and the casing of the switch thereby eliminating the necessity for special anchoring or stabilizing structure for the leads. Two forms of the invention are shown in the accompanying drawings which may be briefly described as follows:

Fig. 1 is a plan view of the device of this invention illustrating the relation of the various parts.

Fig. 2 is a sectional view taken on line 2—2 of Fig. 1.

Fig. 3 is a sectional view taken on line 3—3 of Fig. 1.

Fig. 4 is a plan view of a modified form of the invention.

Fig. 5 is a sectional view taken on line 5—5 of Fig. 4.

The device shown in the drawings has a body 10 comprised of a base 12 and a cover 14. A micro-switch 16, which may be of a generally available commercial type, is secured to the base 12 by such means as screws 18. Also mounted on the base 12 and spaced from the switch 16 is a shiftable regulator element 20 which is preferably in the form of a rotatable cam as shown. The regulator cam has an operating stem 22 extending through an opening in the cover 14 and having at its outer end an operating knob 24 with a flange 26 graduated to indicate temperature settings.

A heat responsive bimetal element 28 having two layers of metal 30 and 32 with unlike thermal expansion characteristics is mounted on the base 12 in the manner of a beam with one end portion engaging the regulator cam 20 and its other end portion engaging the actuator button or plunger 34 of the switch 16. The mounting for the bimetal element lies intermediate the switch and the regulator cam and comprises simply a single stud 36 secured to a projection 38 on the base and to the bimetal element. The stud 36 may advantageously comprise an ordinary screw as shown. The bimetal element preferably has a simple, generally flat plate-like form.

The mounting is arranged to hold the bimetal element in stressed condition for all operative positions of the regulator cam 20. The plunger 34 is biased outwardly by a spring in the micro-switch, which is strong enough to hold the bimetal element in stressed condition, but which yields to heat responsive flexing movements there-

2

of. The micro-switch is very sensitive, being opened and closed by slight movements of the bimetal element 28 and plunger 34. The base 12 has knife-edged projections 40 engaging the sides of the bimetal element 28 and preventing it from pivoting on the stud 36 during use.

The base 12 has portions 42 which provide seats for the casing of the micro-switch (Fig. 2). The base also has recessed means as shown at 44 to contain the lead-in wires or cable 46. The recess 44 is relatively shallow so that when the switch 16 is secured to the base 12 the lead-in cable 46 is firmly clamped between the switch casing and the walls of the recess, as illustrated in Fig. 2. This structure eliminates the necessity of providing a special clamp for stabilizing the lead-in wires within the thermostat body.

In use, the parts are assembled as described above with the lead-in wires connected to the terminals 48 on the switch 16. To place the thermostat in its off position, the control knob 24 is turned so that the flat face 50 of the cam is opposed to the bimetal element 28. In this position, the stress in the bimetal element and the pressure exerted thereby on the plunger 34 are relieved; the plunger is in retracted position, and while the bimetal element may respond to temperature changes, it will not actuate the plunger.

The thermostat is placed in operative position by turning the control knob 24 to bring the rounded portion of the regulator cam 20 into engagement with the bimetal element 28 (Fig. 1). The bimetal element is thus stressed, the stud 36 acts as a fulcrum and the plunger 34 is depressed. The thermostat is set to operate at a selected temperature by turning the control knob 24 to the proper setting as indicated on the graduated flange 26. Turning the control knob shifts the cam 20 and varies the stress in the bimetal element 28 which in turn varies the amount of heat responsive flexure required of the bimetal element to actuate the plunger and operate the switch. The thermostat is turned off by returning the control knob to the off position described above.

The screw 36 provides for a fine adjustment of the stress in the bimetal element and thus provides calibrating means for the graduated flange 26.

In the modified form of the invention shown in Figs. 4 and 5, a bimetal element 60 is secured to a bracket 62 which is pivoted on the base 64 by such means as a pintle or bolt 66. In this form of the invention the stabilizing projections 40 are not needed and are omitted. A screw 68 is threaded through the bimetal element and engages the regulator cam 20 to provide for the fine adjustment of stress in the bimetal element.

I claim:

1. A thermostatic control device having a base and an encased electric switch and switch actuator means mounted on the base, said base having recessed means adapted to receive electric lead wires connected to the switch, and means securing the switch casing to the base with a portion of the switch casing firmly engaging lead wires in said recess whereby to secure the lead wires to said device.

2. In a thermostat of the type having switch means and a regulator element operably interconnected by a heat responsive bimetal element, structure comprising, a body, a heat responsive bimetal element having substantially flat form throughout its entire extent, mounting means securing a generally central portion of said element on said body with both end portions of said element being free, spaced apart switch means and regulator means on said body, one of the free end portions of said bimetal element operably engaging said switch means and the other free end portion of said element operably engaging said regulator means, so that said element extends between said switch means and regulator means.

as a generally flat, simple beam, said parts being arranged so that said mounting means imposes a generally central load on said beam.

3. The structure defined in claim 2 wherein said mounting means comprises a stud transfixing a generally central portion of said bimetal element and being secured on said body.

4. The structure defined in claim 2 wherein said mounting means comprises, a projection on said body, a single screw extending through a hole in a generally central portion of said element, said screw being threadedly secured to said projection and thereby forming calibrating means for said regulator means.

5. The structure defined in claim 4 characterized in that said body has another projection on each side of the first mentioned projection, said other projections engaging edge portions of said bimetal element to support the same against pivotal movement about the axis of said screw.

6. The structure defined in claim 2 wherein said mounting means comprises, a bracket secured to a generally central portion of one face of said element, said bracket being pivotally mounted on said body, the axis of the pivotal mounting being generally parallel to said face of said element.

7. In a thermostat of the type having switch means and a regulator element operably interconnected by a heat responsive bimetal element, structure comprising, a body, spaced apart switch means and regulator means on said body, a heat responsive bimetal element having substantially flat form throughout its entire extent, one end portion of said bimetal element operably engaging said switch means and the other end portion of the element operably engaging said regulator means so that said element extends between said switch means and regulator means as a generally flat simple beam, and means fixing a generally central portion of said element relative to said body, said means securing said element against movement in its plane relatively to said body while enabling said element to flex responsively to loads imposed thereon at said switch means and regulator means.
